UNITED STATES PATENT OFFICE

SAMUEL F. STEIN, OF WILLIAMSPORT, PENNSYLVANIA

OPERATING MECHANISM FOR SEWING MACHINES

Application filed March 15, 1917, Serial No. 155,007. Renewed July 1, 1924.

My invention relates to the driving mechanism of sewing machines, and in particular to power driving mechanism, such as employed in clothes manufacturing and other plants where a gang, or series of machines are driven from the same shaft, and generally stated the object of my invention is to avoid loss of time from the stoppage of the machines for adjusting, or replacing slack, or broken belts and to render unnecessary any repair, or replacing operations at, or in connection with running shafts, or other members where great danger of injury exists, and for the attainment of such object and to secure other advantages which will be apparent when the embodiments of my invention hereinafter set forth in detail and illustrated in the accompanying drawings are understood, my invention consists in the construction substantially as hereinafter specified and claimed.

In the accompanying drawings—

Fig. 1 is a top plan view with portions broken away showing a sewing machine power table construction embodying my invention;

Fig. 2 is a transverse section thereof with parts in elevation;

Fig. 2a is a section on line 2—2, Fig. 2;

Fig. 3 is a detail view in side elevation of a portion of such a power table, but illustrating different location of the driving shaft from that shown in Figs. 1 and 2;

Figs. 4 and 5, are, respectively, detail views illustrating one way by which an additional pulley may be applied to the sewing machine shaft;

Fig. 6 is a detail view in side elevation with parts in section showing a form of slack adjuster of my invention that may be employed;

Fig. 7 is a similar view showing a different form of slack adjuster;

Fig. 7a is a horizontal section on the line 7—7 of Fig. 7;

Fig. 8 is a detail view in vertical section of yet another form of slack adjuster;

Fig. 9 is a horizontal section on the line 9—9 of Fig. 8;

Fig. 10 is a view partly in side elevation

and partly in section of a double slack adjuster provided with a slack measuring device;

Fig. 11 is an end elevation of a slack adjuster that is mounted on the arm of the sewing machine;

Fig. 12 is a section on the line 12—12 of Fig. 11;

Fig. 13 is an elevation showing another construction of slack adjuster applied to the sewing machine arm;

Fig. 14 is a transverse section of a sewing machine power table embodying my invention in which the power is transmitted directly from the main shaft pulley to the sewing machine pulleys instead of through the intermediary of the transmitters and which in the case of Fig. 14, is applied directly to the sewing machine shaft;

Fig. 15 is a detail view partly in side elevation and partly in vertical section of a belt slack adjuster with indicator device that I may employ which indicates the condition of the belts;

Fig. 16 is a horizontal section on the line 16 of Fig. 15;

Fig. 17 is a detail view in section similar to Fig. 8 and showing another form of belt slack adjuster and indicator.

Referring to the drawings I show a double power table of ordinary construction, it comprising cast iron supporting legs 10 and two alining parallel series of table tops 11, each adapted to support a sewing machine 12 and having a main driving shaft 13 running longitudinally of the series of tables and situated between the two series of tables and being driven continuously by power applied to a band wheel 14 at one end thereof. For each sewing machine there is a treadle controlled transmitter through which power from the continuously running driving shaft 13 may be transmitted at the will of the operator to the sewing machine, and in the usual practice there is a pulley for each sewing machine on the driving shaft 13 belted to a pulley on the transmitter and there is a second pulley on the transmitter belted to a pulley on the sewing machine shaft adjacent the hand wheel thereof. With such ordinary

construction when a belt becomes slack, work on that machine must be stopped and the slack condition remedied by cutting out the surplus portion of the belt and replacing it. 5 Usually there is a mechanic whose duty it is to look after such matters, and he, of course, may be busy elsewhere, thus prolonging the disuse of the machine, and he must do the work of replacing while the main driving shaft and its pulleys are revolving, and thus 10 is exposed to danger of injury. In cutting the belt to remove the excess slack portion, too much may be removed. Again, a belt may break and great effort will have to be expended to place the belt on the pulley, which 15 increases the probability of getting caught with the revolving pulley and shaft, and even after the belt has finally been placed on pulley on account of its tightness it is liable to break most any moment and hence a new 20 belt will be required, and involve the same consequences as to disuse of the sewing machine and danger in supplying the belt. Instead of using a single belt to transmit power 25 from main shaft to transmitter and from transmitter to sewing machine, I use more than one, and preferably more than one in each case. Thus, as shown in the drawings, on the main shaft 13 I place a pulley with 30 two grooves, or two grooved pulleys 15 and 15^a side by side and provide two pulleys 16 and 16^a side by side on the transmitter, thus providing two pairs of pulleys, 15 and 16 being one pair and 15^a and 16^a, another pair, 35 and each pair being connected by its own belt 17 or 17^a, and I also place on the transmitter two pulleys 18 and 18^a side by side and upon the sewing machine shaft two pulleys 19 and 19^a side by side, thus providing two pairs of 40 pulleys from the transmitter to the sewing machine shaft, and each pair having its own driving belt, 20 or 20^a. If one of the belts 20 and 20^a breaks, or becomes too slack to drive, the sewing machine will nevertheless not be 45 stopped because the remaining belt will continue in operation and the slack, or broken belt can be attended to at some convenient time when the machine is not in use and shaft not revolving, as, for example, at the end, or 50 before the beginning of the day's work. Moreover, my employment of a plurality of belts, by reason of the division of labor between them adds to their working longevity. If desired, by using a fast and loose pulley 55 arrangement, both belts need not be used to transmit power at the same time, but only one which would work on the fast pulley, and if that one should break, then the other on the loose pulley would be shifted to the fast 60 pulley and thus become the driving belt.

The transmitter is operated to connect power to the sewing machine, as usual by a treadle 21, which through a connecting rod, or link 22 rocks a lever 23 which presses the 65 set of wheels 16 and 16^a into engagement with

the set of wheels 18 and 18^a; when the treadle is released a spring 24 effects the disengagement of such wheels. The lever 23 has a brake finger 25 which is moved into and out of contact with the rim of one of the pulleys 18 to stop and release the latter.

To employ the additional belt as far as the sewing machine is concerned, it is necessary merely to add a second pulley on the band wheel shaft alongside the pulley already provided, as illustrated in Figs. 4 and 5, so that no special construction of the sewing machine in that regard is necessary and machines already constructed may be utilized. Thus as shown in Fig. 4, the additional pulley 190 75 may be slipped over and secured by screws to the hub ordinarily present on the sewing machine wheel. The fastening screws can be run radially, as shown in Fig. 4, or attaching means otherwise applied may be employed. 80 The additional pulley for the transmitter 85 may be similarly provided.

The main driving shaft 13, may, as in ordinary practice, be supported from the floor by bearing brackets 26, as shown in Fig. 3, but an important feature of my invention, as shown in Figs. 1 and 2, is the location of said shaft in a trough, or depression 27, in the sewing machine table top and thus the constantly running shaft 13 and the pulleys thereon are housed, or put in a condition of safety without the necessity of providing a special housing which location near the floor necessitates, and which is required by the insurance companies for the proprietor to get a lower rate of insurance than is required if such parts are not safeguarded. Said trough as best shown in Fig. 2, consists usually of a bottom and sides which extend from the underside of the table top to the bottom, and the shaft hangers, or brackets 28 may be readily supported from the table legs below the bottom, a suitable opening being provided in the bottom for the passage into the trough of the hanger standard. It is not necessary, for the purpose of my invention, that there be a bottom to the trough. See Fig. 14. The upper side of the trough 27 is closed by a cover that may consist, as best shown in Fig. 1, of stationary, or fixed sections 29 reaching between opposite tables and hinged sections 30 situated directly above the pulleys 15 on the driving shaft, the hinged sections being provided to give access to the pulleys for the application of the belts there-to, or tightening pulleys to the shaft. Said hinged sections are hinged on an axis extending transversely of the table so that when the sections are thrown open, or raised they are not moved towards the sewing machines, 115 and hence, involve no disturbance of the opposite sewing machine operators. The stationary sections may be used for thread stands, or put to any other desired use. Said stationary sections may be omitted, if de- 120 125 130

sired, in which case there will be vertical walls or partitions at the ends of the hinged sections. The location of the driving shaft in the trough renders the oiling of bearings thereof very convenient because the bearings being close to the top of the trough an oil hole may be provided in the stationary section 29 directly above the oil hole of the bearing below so that the oil may be supplied from the top of the table, as by an ordinary oil can with a long nozzle, or an oil can 29 placed and kept in a conical hole in the table top in an inverted position so that oil may drip therefrom to the bearing.

Another important feature of my invention is the provision of a device for taking up the slack of the belts from the main driving shaft to the transmitter and from the latter to the sewing machine shaft, or in the case of either of such belts I illustrate in the drawings various forms of slack adjusters applicable to both sets of belts. Those shown in detail in Figs. 6 to 10 are applied to the sewing machine table and include a belt-engaging roller, or rollers located beneath the sewing machine table and a roller-carrying arm, or shank passing through an opening in the table top and extending to the upper side thereof where it is provided with means for manipulating, or adjusting it to move the position of the roller to take up the belt slack. In such cases the slack adjuster is mounted upon the hinged covers 30 and the belt-engaging rollers bear upon the upper side of the belts so that the hinged covers 30 may be readily opened. In the device shown in Fig. 6, there is a single belt-engaging roller 32 of cylindrical form and of such length as to engage both belts and to allow a certain amount of lateral change of position and the roller is mounted on a pintle formed integral with a shank, or stem 33 which passes upward through a hole in the table top section 30 and through a metal box 34 in which is journaled a vertical screw 35 that engages thread-like notches 36 in the adjacent side of the shank 33 so that by revolving the screw 35 the shank and roller may be adjusted and this adjusting device is obviously selflocking. The shank 33 may have graduations 33a cooperating with the top surface of the box which are so related to the taut, or tight condition of the belt and changes therefrom to indicate in inches the amount of slack required to be removed. Thus the mechanic, or workman may have an accurate measure of the quantity of the belt to be cut out and thereby avoid the danger of cutting too much and ruining the belt.

The slack adjuster shown in Fig. 7 consists of a vertically movable shank 37 which below the table has a horizontal pintle in the form of a bolt 38 secured to such shank upon which pintle is an idler roller 39 for each belt and the rollers are loose on the bolts so

that they may move axially to compensate for any inaccuracy in the attaching, or mounting of the shank 37 on the table. Above the table, the shank 37 passes through a box 40, and a set screw 41 is provided for clamping the shank 37 at the desired point of adjustment, the screw engaged surface of the shank being flattened so as to prevent turning of the shank.

In Fig. 8 I show a form of slack adjuster that is automatic, it having a roller-carrying shank 42 which extends above the table top into a sleeve 43 closed at the top by a screw plug 44 and between which plug and shank 42 is interposed a coil spring 45 which normally acts to press the shank 42 in the direction to cause the belt acted thereon to be tightened. The screw plug 44 is employed so that the tension of the spring 45 may be adjusted. As the shank 42 is round, means are provided to prevent turning thereof, and hence, displacement of the belt-engaging roller, which as shown, consists of a radial lug, or pin 46 that engages a slot 47 in the sleeve 43.

As shown in Fig. 10, the shank 48 which carries the belt-engaging roller, or device, has its portion above the table top threaded and engaged by a nut 49 swiveled in a box 50 so that by revolving the nut, the shank 48 is moved longitudinally and above the box 50. At the upper end of the shank there is a lug 51 which points in the same direction in which the belt-engaging roller axis lie, so that the operator can see exactly what the relative position of the roller is to the belt engaged. The slack of the belt 20 running to the sewing machine shaft may be taken up by the device shown in Fig. 10, said device comprising a belt-engaging roller 52 carried by an arm 53 hinged to the base plate of the box 50, and which arm 53 carries a clamping screw 54 which passes through an arcuate slot 55 in an arm 56 and thereby the roller 52 secured at the desired adjustment. As in the case of the device shown in Fig. 6, a scale, or indicator is provided to measure the amount of slack to be removed, said indicator comprising a scale 57 on the arm 56 and an index, or pointer 58 on the arm 53 which coacts with said scale. A spring 56a may be provided to press on the arm 53 so as to make the slack adjuster automatic.

As shown in Figs. 11 and 12, the slack adjuster is shown applied to the belt 20 running to the sewing machine shaft pulley, in which case it consists of a belt-engaging roller 59 carried by an arm 60 adapted to be secured at the desired point of adjustment by a clamping screw 61, which passes through a slot 62 in the arm and into the adjacent wall of the arm of the sewing machine. Adjustment may be done by sliding the arm lengthwise, due to the slot, or by rocking the arm 60 on the screw as a pivot.

As shown in Fig. 13, there is a lever 63 piv-

oted to the sewing machine arm between its ends which carries on each side of its pivot a belt-engaging roller 64 so that both runs of the belt are engaged by a roller and a spring 65 is provided that bears upon said lever and automatically moves the lever in the direction to take up the slack. The pivot of said lever is preferably a clamp screw 66 so that if desired the lever may be clamped to the position to which it may be moved, in which case its automatic action will not be utilized. The position of the spring 65 is such that should the belt break and the lever 63 swung by the reaction from the breaking of the belt, the spring will stop the swing of the lever 63, and thus prevent any probability of striking the operator. As shown in Figs. 2 and 2^a, a similar device is employed consisting of a lever 630 with rollers 640 and 641 on opposite sides to engage different belts. The pivot screw 650 passes through a slot 651 in the lever, so that by shifting the lever lengthwise and also turning it the desired tension may be put on either belt without interference with the other.

It is preferable in order to allow for the play of the belts in taking up slack to cut slots for the passage of the belts through the table tops, or walls, and on the outer side or top surface of the table to face these slots with slotted metal plates 68, as shown in Fig.

1. As shown in Fig. 1 in dotted lines the table may have a leaf, or extension 69 to form a guard for the main shaft driving wheel 14.

With the location of the shaft 13 in the trough 27, the belts running from the pulleys on such shaft are invisible, and hence, their condition as to slackness is not open to view. I, therefore, propose to use an indicator with a slack adjuster which will disclose the state of such belts. As shown in Fig. 15 I employ a vertical bar 70 which extends above and below the table top through a hole therein and through a box 71 fastened to the top of the table, and which through one of its walls has attached a clamping screw 72 by which the vertical position of the bar 70 may be fixed at different vertical adjustments and pivoted to the lower end of said bar 70 on opposite sides thereof are two angle levers 73, the short arm of each of which carries a roller 74 that bears upon the adjacent belt 75, or 75a while the long arm of the lever extends vertically (one on each side of the bar 70) and terminates at its upper end in an index, or pointer 76 that preferably projects a short distance above the top of the bar 70. A spring 77 pressing against the longer arm of the lever 73 yieldingly forces its roller 74 against the belt. It will thus be seen that change in tension of the belt 75 will cause the pointer 76 to swing over a scale of marks having suitable characters to indicate the different degrees of tension, or the condition of the belt.

Thus, the letter "T" may be used to indicate

that the belt is tight, so that when the pointer 76 is adjacent the letter "T" it is known the belt is in proper condition, the letter "L" may be used to indicate an objectionably loose condition to which the pointer points when that condition exists, and the letter "O" may be used to indicate that the belt is off and to which letter the pointer swings when the roller 74 is not in contact with the belt 75. A stop pin 78 projects on both sides of the bar 70 in the path of the long indicator arms of the levers 73 and stops them when they are in that limit of their swing which indicates that the belt is properly tight while permitting their free movement in the opposite direction to indicate other states of the belt.

In Fig. 17 a form of device is shown corresponding to that illustrated in Fig. 8, excepting that instead of a single shank corresponding to the shank 42, there are two shanks 79a, each provided at its upper end with an outwardly projecting lug 80 fitting a vertical slot 81 in a sleeve 82, and each of said lugs constituting an indicator to co-operate with a series of indicators consisting of letters, as shown, "T" "L" and "O" to serve to indicate the state of tension, or condition of the belt. On top and bottom of the table there are washers, or plates 83 provided with alining holes for the respective shanks 79a.

As indicated in Figs. 1 and 2, in a space provided in consequence of lifting the shaft 13 and its pulleys, I place heating pipes 84, the same being supported in holes provided in the table legs for that purpose. Thus the heating pipes are given a location where they are out of the way and yet are most advantageously located for heating purposes, and if desired to protect surfaces above them from excessive heat, such surfaces may be covered with asbestos.

As shown in Fig. 14, I illustrate my invention as embodied in a power table for sewing machines where the transmitter 85 is mounted directly upon the sewing machine shaft and thus a set of single belts 86 may be run from the driving pulleys 130 on the main shaft 131 to the transmitter, said belts 86 being passed over idler pulleys 87 to change their direction and the belts 86 on one side of the table being crossed to give the proper direction of revolution to the transmitter. The transmitter shown is of known construction having a pulley shifting lever 88, and in lieu of the usual friction brake arm thereon I provide a finger 89, adapted to act as a positive stop by engaging a projection 90 on the hand wheel 91 of the machine so that the sewing machine needle will always stop in a desired position, either out of the goods or in them. Two projections 90 may be used, to stop the needle in either position, but one of which is active at a time, or in place, or as shown, one may be used and shifted to oc-

cup either position. In sewing short pieces such as flaps, buckle-straps, etc., where sharp turns or change of direction of the line of stitching is required, such turns can advantageously and readily be made by using the needle as a pivot, when it is stopped down in the goods. On the side of the finger 89 toward which the projection 90 moves, I provide a spring 92, over which the projection 10 rides before it is arrested by the finger. This cushions the blow of the projection, and it also enables the hand wheel 91 to be readily turned backward, as might be necessary for lifting the needle, as when the sewing thread 15 breaks and the needle is in the goods. Said projection 90 is preferably a roller of suitable material, so as to ride easily and noiselessly.

The transmitter lever 88 is acted upon by a spring 88^a; so the transmitter is normally 20 inactive, and movement of the lever to render the transmitter active is, as usual, effected by a treadle. Upon release of the treadle, the lever 88 swings and puts its stop finger 89 in the path of the projection 90. The parts are 25 so arranged and timed that the finger 89 is moved out of the path of the projection 90, at or just before the lever 88 acts to throw on the power to the machine, when the latter is to be started up.

30 As shown in Fig. 1, the main driving pulley 14 may be provided with two belts 93 alongside of each other, and which may be separated by a flange 94 at the middle of the face of the pulley, the two belts being provided on 35 the same principle of the multiplication of the belts connecting the driving shaft and the sewing machines.

The location of the shaft 13 near the top of the table is of great advantage in that the 40 workman has access thereto and the pulleys and belts thereon from the top, so that awkward tiresome bending over of the body is unnecessary and, hence, comfort as well as safety of the workman is assured, and no disturbance is caused of the sewing machine 45 operator while at work.

When the transmitter frame is bolted to the underside of the table as shown in Fig. 2 of the drawing it is an awkward job to hold 50 the frame in position because of its weight while putting the bolts through the frame into the underside of the table top. I, therefore, provide on said transmitter frame 95 a vertical flange 96 which abuts against the 55 outer edge of the table top and through which screws, or bolts, 97 are passed sidewise into the table top. It will be seen that with this upstanding flange 96 it is an easy matter to place the frame in proper position and to 60 fasten it first by putting in the screws, or bolts, 97, and then afterwards putting in the bolts 98 from the underside which enter the underside of the table top, which bolts 98 are the ones depended upon to support the transmitter frame in position.

As shown in Figs. 2 and 14, a guard, or shield in the form of a plate 99 may be provided as a safeguard against contact of operator with the pulleys and belts adjacent thereto.

Of course, the relative dimensions of the pulleys and the form of the pulleys may be varied without departure from my invention.

Having thus described my invention what I claim is—

1. As an improvement in power mechanism for sewing machines, the combination of a driving shaft, a plurality of pulleys thereon, a plurality of pulleys through which power is transmitted to the same sewing machine, and belts connecting the driving and driven pulleys in pairs each belt alone being able to transmit the required driving power.

2. As an improvement in power mechanism for sewing machines, the combination of a driving shaft, a plurality of pulleys thereon, a transmitter comprising a corresponding number of driven pulleys, belts connecting the driving and driven pulleys in pairs each belt alone being able to transmit the required driving power, and means for transmitting power from the transmitter to the sewing machine.

3. As an improvement in power mechanism for sewing machines, the combination of a driving shaft, a plurality of pulleys thereon, a transmitter comprising a corresponding number of driven pulleys, belts connecting the driving and driven pulleys in pairs each belt alone being able to transmit the required driving power, and means for transmitting power from the transmitter to the sewing machine, also comprising a plurality of driving pulleys and driven pulleys on the sewing machine shaft and belts connecting them in pairs.

4. As an improvement in power mechanism for sewing machines, the combination of a driving shaft, means for transmitting power from the shaft to the sewing machine, comprising belt connected pulleys, a slack adjusting device for the belt, and means associated with said slack adjusting device to measure the amount of slack.

5. As an improvement in power mechanism for sewing machines, the combination of a driving shaft, means for transmitting power from the shaft to the sewing machine, comprising belt connected pulleys, a slack adjusting device for the belt, and means associated with said slack adjusting device to indicate the state of the belt.

In testimony whereof I affix my signature.
SAMUEL F. STEIN.
